Inventor E. F. Bernhardt

UNITED STATES PATENT OFFICE

125,147

DESIGN FOR A POST CARD CHECK BLANK

Elmer Frederick Bernhardt, Baltimore, Md.

Application September 28, 1940, Serial No. 95,514

Term of patent 14 years

To all whom it may concern:

Be it known that I, Elmer Frederick Bernhardt, a citizen of the United States, residing at Baltimore city, in the State of Maryland, have invented a new, original, and ornamental Design for a Post Card Check Blank, of which the following is a specification, reference being had to the accompanying drawing, forming part thereof.

Figure 1 is a plan view of a post card check blank showing my design. Figure 2 is a view of the opposite side of the post card check blank shown in Figure 1.

I claim:

The ornamental design for a post card check blank, as shown and described.

ELMER FREDERICK BERNHARDT.
